UNITED STATES PATENT OFFICE

158,572

BELT

Morris Guzik, New York, N. Y.

Application May 4, 1948, Serial No. 146,155

Term of patent 3½ years

(Cl. D3—10)

To the Commissioner of Patents:

Be it known that I, Morris Guzik, a citizen of the United States, residing at New York, N. Y., have invented a new, original, and ornamental Design for a Belt, of which the following is a specification, reference being had to the accompanying drawing, forming part thereof.

The figure on the drawing is a front perspective view of a belt showing my new design.

The back of the belt is conventionally plain.

I claim:

The ornamental design for a belt, as shown and described.

MORRIS GUZIK.
